FIG. I

FIG. 2

Robert F. Metcalfe³

By R. L. S.

Attorney

UNITED STATES PATENT OFFICE.

ROBERT F. METCALFE, OF ERIE, PENNSYLVANIA.

BURNER.

1,416,734.

Specification of Letters Patent. Patented May 23, 1922.

Application filed July 25, 1919. Serial No. 313,422.

To all whom it may concern:

Be it known that I, ROBERT F. METCALFE, a citizen of the United States, residing at Erie, in the county of Erie and State of Pennsylvania, have invented new and useful Improvements in Burners, of which the following is a specification.

This invention relates to burners and consists in certain improvements in the construction thereof as will be hereinafter fully described and pointed out in the claims.

More particularly the invention relates to that type of burners used for developing heat and supplied by a combustible mixture 15 from a fuel jet.

In some respects the invention is an improvement on the structure shown in my application #249,777, filed Aug. 14, 1918.

The invention is illustrated in the accompanying drawings as follows:—

Fig. 1 shows a plan view.

Fig. 2 a section on the line 2—2 in Fig. 1, a part being broken away to the line 2^a—2^a.

Fig. 3 a section on the line 3—3 in Fig. 2. 25 1 marks the furnace, 2 the flame opening to the furnace, 3 a burner pocket in the furnace wall, 4 the burner, 5 the burner chamber, 6 the venturi having its point of greatest contraction at 7, 8 a fuel jet, 9 an air 30 pipe leading to the fuel jet, 10 the fuel supply for the fuel jet and 11 the spark plug for igniting the mixture in the burner.

It is desirable to have the burner provided with means whereby the pilot flame may be 35 maintained with a very slight flow of fuel so that the walls of the burner may be kept at an operative temperature. This is supplied in the present instance by the pilot flame openings 12 in the walls of the chamber 5. A valve 13 is arranged in the chamber immediately in front of the pilot flame 40 openings and this valve is initially closed. A spider, or web 14 couples the valve 13 with a cylindrical valve 15 opening through 45 its center. These valves are so placed that as the valve 13 is opened the valve 15 closes the pilot flame openings 12.

The valves are connected with a rod 16. This rod extends to a piston 17 arranged in 50 the cylinder 18. A spring 19 operating against the piston holds the valve 13 in an initially closed position and the valve 15 initially in position to uncover the openings 12. An air supply pipe 20 leads to a fitting 55 21 which in turn leads to the cylinder and

from which are arranged the branches 22 leading to the pipes 9.

The main flame opening nozzle carrier 23 is slidingly mounted in the end of the burner chamber and the nozzle 24 itself is spaced 60 from the walls of the chamber so that this nozzle being as it is more or less insulated from the walls of the chamber is cooler than the walls of the chamber.

The nozzle is coupled with the valve 13 by 65 the webs 25. Burner heating flame openings 26 are arranged in the walls of the burner between the valve 13 and the nozzle 24. These are just sufficient in number to give sufficient flame to maintain the burner at 70 the most desirable temperature for operation. As compared with the area of the main flame openings the area of the openings 26 is comparatively small. The operation of the device is as follows: Fuel is 75 turned on, ignited from the spark plug 11 and burns initially within the burner to heat it to operative temperature and then shifts to an outward flame somewhat in the manner of the burner of my former application. 80 It will be noted that as the air is turned on with more than initial volume the pressure on the piston 17 is sufficient to open the valve 13 and close the valve 15. Under these conditions there is a main flame through the 85 opening or nozzle 24 and a minor flame through the openings 26 to keep the burner at operative temperature. It will be understood that the fire through the openings 12 may be of any volume desired giving a small 90 heat to the furnace or just sufficient to maintain ignition. In any event the burner is maintained at an operative temperature.

The Venturi tube should be proportioned in size to the air pressure used in the jet. 95 Better results can be obtained with comparatively small Venturi tubes and moderate air pressures. In order to get sufficient volume of combustible mixture to the burner the number of Venturi tubes may be increased. I prefer, therefore, to provide a plurality of Venturi tubes with fuel jets rather than to enlarge the jets and tubes for the burner.

What I claim as new is:—

1. In a burner, the combination of a burner chamber having a main flame opening and a pilot flame opening, the flame from said pilot flame opening being positioned to maintain the walls of the chamber 110

- at an operative temperature; and means for injecting a combustible mixture to the chamber.
2. In a burner, the combination of a burner chamber having a main flame opening and a pilot flame opening, the flame from said pilot flame opening being positioned to maintain the walls of the chamber at an operative temperature; a valve between said openings; and means for actuating said valve.
3. In a burner, the combination of a burner chamber having a main flame opening and a pilot flame opening; a valve between said openings; means for supplying fluid for combustion under pressure to said burner; and devices actuated by the fluid as supplied by the burner for actuating said valve.
4. In a burner, the combination of a burner chamber having a main flame opening and a pilot flame opening; a valve between said openings; means for supplying fluid for combustion under pressure to said burner; devices actuated by the fluid as supplied by the burner for actuating said valve; a second valve controlling the pilot flame opening; and means actuating said second valve.
5. In a burner, the combination of a burner chamber having a main flame opening and a pilot flame opening; a first valve between said openings; a second valve controlling the pilot flame opening; means for supplying fluid for combustion under pressure to said burner; and devices actuated by the fluid as supplied to the burner for actuating said valves.
6. In a burner, the combination of a burner chamber having a main flame opening and a pilot flame opening; a first valve between said openings; a second valve controlling said pilot flame opening; means for coupling said valves together; means for supplying fluid for combustion under pressure to said burner; and devices actuated by the fluid as supplied to the burner for actuating said valves.
7. In a burner, the combination of a burner chamber having a main flame opening and a burner heating flame opening, the flame from the main opening being projected away from the burner walls and the flame from the burner heating flame opening being in position to heat the chamber walls; and means for supplying combustible mixture to the burner.
8. In a burner, the combination of a burner chamber having a main flame opening; a burner heating flame opening and a pilot flame opening; means for supplying combustible mixture to the burner; a valve between the burner heating flame opening and the pilot flame opening; and means for actuating said valve.
9. In a burner, the combination of a burner chamber; a plurality of flame openings; means within the burner for opening and closing some of said openings; means for injecting a combustible mixture to the burner; and means for igniting the mixture in the burner; said openings being proportioned to sustain combustion within the burner initially and to transfer the flame from the burner to without the burner as the walls of the burner chamber become heated.
10. In a burner, the combination of a burner chamber having a main flame opening and a pilot flame opening; a main flame opening nozzle slidingly mounted in the main flame opening; a valve coupled with said nozzle, said valve being located between said openings; and means for actuating said valve and nozzle.
11. In a burner, the combination of a burner chamber having a main flame opening; a mixture nozzle having its end spaced radially from and out of contact with the walls of said opening; means for heating the walls of the burner chamber; and means for injecting a combustible fluid to the chamber.
12. In a burner, the combination of a burner chamber having a main flame opening; a mixture nozzle loosely mounted in the opening; and means for injecting a combustible mixture to the chamber.

In testimony whereof I have hereunto set my hand.

ROBERT F. METCALFE.
